(57) **CLAIM**

The ornamental design for a pressure regulator, as shown and described.

DESCRIPTION

FIG. 1 is a perspective view of the front, right side and top of a pressure regulator showing an embodiment according to the new ornamental design;

FIG. 2 is a top view thereof;

FIG. 3 is a bottom view thereof;

FIG. 4 is a front view thereof;

FIG. 5 is a rear view thereof;

FIG. 6 is a right side view thereof;

FIG. 7 is a left side view thereof; and,

FIG. 8 is a perspective view of the front, right side and bottom thereof.

The broken lines within the Figures show portions of the pressure regulator which form no part of the claimed design.
